UNITED STATES PATENT OFFICE

WILLIAM M. THOMAS, OF ALBUQUERQUE, NEW MEXICO, ASSIGNOR OF ONE-FOURTH TO FRED W. LEE AND ONE-FOURTH TO BRYAN G. JOHNSON, BOTH OF ALBUQUERQUE, NEW MEXICO

CARBURETOR

Application filed November 18, 1930. Serial No. 496,541.

This invention relates to a device for intimately mixing a liquid and a gas and more particularly to the type of mixers known as carburetors, which are extensively used on 5 internal combustion engines for automobiles, for mixing a liquid fuel such as gasoline with a gas such as air with which it will explosively react under proper conditions.

In the type of internal combustion engine 10 ordinarily used in automobiles the engine is so designed that its speed and the consequent speed of the car may be varied within a rather wide range by merely varying the amount of explosive mixture supplied to the 15 engine by the carburetor. The carburetor therefore must be designed to supply this explosive mixture at a rate which may be varied at the will of the operator. The usual type of carburetor attempts to accomplish 20 this result by injecting into the air passage a finely divided spray of liquid fuel.

It may be noted here, however, that the explosive mixture used by internal combustion engines produces its maximum effect 25 only when the percentage of fuel in the explosive mixture is exactly right for the particular speed at which the engine is operating and that the same mixture will not give maximum power at all speeds. With a system of 30 carburetion such as is in general use it is the usual practice to adjust or proportion the fuel nozzles so that a proper amount of fuel is injected into the air to give maximum efficiency at the average running speed. With 35 such systems there is no assurance nor any reason to believe that the proper mixture will be supplied to the engine over any appreciable range of speeds. The fact that a proper mixture is not supplied to the engine at all 40 times is clearly shown by the fact that frequently when the engine is running at an idling speed and the butterfly valve is quickly opened, the engine will "stall" because an improperly proportioned mixture has been 45 supplied thereto.

In some of the carburetors of the aforementioned type in order to produce a finer dispersion of the fuel in the air the passage in which the dispersion is made has been 50 formed into the shape of a Venturi tube, that

is with a smaller or constricted section which tapers gradually into a section of larger cross section or diameter. The nozzles from which the fuel is dispersed or atomized are then located near the smallest part of the constriction and as the expansion of the air on passing the constriction increases the suction upon these nozzles they may consequently be made smaller and still supply the same amount of fuel. It has been found that these smaller 55 nozzles together with the expansion of the air cause a more intimate mixture of the air and fuel and consequently a better and more powerful explosive mixture.

The present invention relates primarily to 60 a means for obtaining an intimate mixture of air and liquid fuel and to such means as will also insure that the proportion of dispersed fuel in the explosive mixture will at all times be exactly that required for maximum efficiency regardless of the speed at 65 which the engine is running. This is accomplished by a novel construction of that section of the passage through which the air or other gas travels before it reaches the manually operated butterfly valve and in which 70 section of the passage the gasoline or other fuel is atomized or dispersed in the air.

As already stated, by varying the shape of 75 this passage and the spacing and arrangement of nozzles in the passage, it has been found possible to draw from the nozzles an amount of fuel equal to almost any desired percentage of the air passing through the passage. However, the amount of air passing through the passage varies greatly with 80 the speed of the motor and for the most efficient operation it is essential that as the speed of the motor and consequently the rate of flow of air through this passage varies, 85 the amount of fuel drawn from the nozzle or nozzles will be varied in such an amount that there is supplied to the motor at whatever rate of speed it is revolving, a supply of explosive mixture containing exactly the 90 right proportion of fuel and in which the fuel is completely dispersed in the air.

In the carburetors in general use today it 95 is customary to bring the air into the carburetor from a horizontal direction and then 100

turn it at right angles flowing it upward past the butterfly valve and then into the motor. The jets which supply the gasoline to the air are usually located just past the point in the 5 passage where it turns from horizontal to vertical and the constricted portion of the passage is usually at this point.

In the applicant's copending application Serial Number 462,536, filed June 20, 1930, 10 there is disclosed a construction of the passage in the carburetor at this point by which construction the air flowing through the passage is divided into two parts, a part of which flows through a short constricted opening in the center of the passage and in which opening are located the ends of the fuel supplying nozzles and the other part of the air flows through supplemental openings in a shoulder which surrounds the central constricted 15 opening. The central opening then flares abruptly thus causing a suction above the nozzles when air is passed therethrough and the supplemental openings converge towards the center of the passage, thus directing streams of air into the fuel and air mixture and causing a thorough intermixing as well as adding to the suction effect upon the nozzles. By proper proportioning of these 20 nozzles and openings it has been found possible to obtain a more desirable mixture of gasoline and air over a much greater range of speeds than is possible with the ordinary carburetor.

In the present invention the applicant is 25 again dealing with the problem of the construction of the part of the passage through the carburetor in which the gasoline and air are mixed and in this invention the nozzles which supply fuel to the incoming air terminate near the center of a ring of material so shaped as to form a very short constricted passage opening abruptly into the main passage on either side. The outer part of this 30 ring is formed of radially extending flanges between which air may pass from the passageway on the incoming side of the ring to the passageway on the outgoing side of the ring. These flanges do not extend vertically 35 but spiral around the axis of the ring helically. The passage in which the ring is situated may be slightly smaller on the outlet side of the ring and taper to this smaller diameter immediately above the ring or a slight constriction may be formed in the passageway immediately above the ring. When 40 air is passed through the carburetor a portion of it enters the central opening in the ring and by its passage therethrough and its expansion upon reaching the outlet side of the ring draws fuel with it in an atomized state 45 from the nozzles. Supplemental jets of air are formed by the passageways between the radial fins on the ring and are given a whirling motion by these fins and an inwardly directed motion by the tapered wall or con-

striction of the passage and thus add to the suction over the nozzles and assist greatly in mixing the air and fuel. The number and spacing of these fins on this ring and consequently the resistance offered to the air flowing therethrough may be varied to vary the mixture which the carburetor will form and the number of fins on the different sides of the ring may likewise be varied in order to balance the amounts of air flowing through the ring and cause the same amount of air to flow through on all sides. This is especially desirable in a carburetor of the form shown in this and the applicant's aforementioned copending application, as in the type of carburetor shown therein, which type of carburetor is in general use today, the air entering the carburetor has a shorter path of travel to one side of the ring than to the other and consequently a greater amount of air 85 will tend to pass through the side of the ring which is closest to the entrance passage. This effect may be balanced by placing more fins or wider fins on this side of the ring and hence limiting the area of the openings. 90

This carburetor, then, provides a device which supplies an even flow of air and consequently an even pull on the fuel supply jets and by the action of those supplemental jets which add to the suction and the mixing 95 effect of the main opening it permits the main opening to be made of larger diameter and shorter so that the resistance to air flowing through the carburetor is materially lessened and hence more readily supplied to 100 the motor on opening the butterfly valve and at the same time provides a means which adjusts the mixture automatically to that which is best suited to the motor at the particular speed at which it is revolving. This latter is true because by properly balancing the amount of air supplied through the supplemental openings and the main opening the suction on the fuel supply nozzles can be caused to vary with the speed of the motor 105 in just such relation to the speed of the motor that the right amount of fuel will be supplied at all speeds.

The use of a slight constriction in the passageway above the ring rather than the tapered section permits an expansion of the gas upon passing the constriction which is often found desirable. The applicant's invention also includes, when desirable, the provision of a completely separate passage in the carburetor whereby the air which is supplied to the central opening in the ring is supplied from a completely different source than that which supplies the air to the supplemental openings around the periphery. This, as the applicant has shown it, comprises a passageway leading from the opening in the center of the ring directly through the bottom of the carburetor and the original passageway is thus left to supply the supplemental open- 110

ings only. The advantage of this construction is that the air supplied to either the supplemental openings or the central opening may be varied at will and with this construction it is possible to manually decrease or increase the amount of air flowing through one of the two openings and thus effect a substantial change in the fuel-air mixture produced. It is possible and often desirable to connect the central opening to a heater so that the air supply through this opening may be suitable for starting the motor and a damper or valve may be placed in the passageway supplying the central opening in order that the amount of air supplied through this opening may be decreased thus decreasing the amount of gasoline supplied to the mixture.

This type of carburetor is also particularly adapted to be used with air supplied under pressure by a supercharger which may be connected to either or both of the passageways but preferably to the passageway supplying the supplemental openings and in this case it is often found advisable to place a valve in the passageway leading to the central opening in order to control the amount of air entering that opening and hence the amount of fuel supplied to the mixture. A super-charger in such a construction is preferably controlled in some suitable manner so as not to blow air back through the central opening when the butterfly valve is closed. The supercharger may also be used with a carburetor of the construction first described in which case all of the air is fed to the carburetor under pressure.

In order to give a detailed description of this new carburetor reference is made to the accompanying drawings in which several forms are shown which are illustrative of embodiments of the applicant's invention.

Fig. 1 illustrates a carburetor of the applicant's improved type shown in side elevation with certain parts in cross section.

Fig. 2 is a top sectional view of the same construction taken on the line 2—2 of Fig. 1.

Fig. 3 is a perspective view of the ring which causes the mixing of the fuel and air and replaces the old Venturi tube.

Fig. 4 illustrates a modified form of the applicant's invention being a side elevational view with certain parts in cross section.

Fig. 5 shows a cross section of a part of this new construction taken on the line 5—5 of Fig. 4 and looking downward.

Fig. 6 is a bottom view of the modification of the carburetor shown in Fig. 4.

Fig. 7 illustrates more or less diagrammatically a supercharger or blower attached to a carburetor of the type shown in Fig. 4 so as to supply air under pressure to the openings between the radial fins.

Fig. 8 is a side elevational view partly in section showing a slightly modified form of

the applicant's carburetor in which a collar forming a constriction above the ring takes the place of the tapered wall of the passage.

Fig. 9 is a top sectional view of the embodiment of Fig. 8 taken on line 9—9 of that figure.

Fig. 10 is a bottom view of the ring in the embodiment shown in Fig. 8.

In the drawings the carburetor is composed of two castings 1 and 2 which house a suitable float mechanism in a chamber 3 formed in casting 1. This float mechanism is adapted to supply liquid fuel to the mixing device at a constant pressure. Being of the conventional type the float chamber is not shown in detail. The castings 1 and 2 further provide an air passage 4 comprising a horizontal passage and a vertical passage joining each other at right angles. Air is adapted to enter at the end 5 of the horizontal passage and to flow therethrough into the vertical passage and through the vertical passage through exit 6 of the carburetor from which it is led by a manifold to the internal combustion engine. Near the entrance end 5 of the passage 4 is located a conventional choke valve 7 which is adapted to reduce or cut off the supply of incoming air and near the exit 6 of the passage is located a conventional butterfly valve 8 for regulating the amount of explosive mixture supplied to the engine. Adjacent the butterfly valve 8 is a small opening 9 through which an amount of explosive mixture sufficient to supply the motor when idling is supplied.

Located within the passage 4 near the turn therein and extending upward from the bottom of the passage into close proximity to the point where the vertical passage begins are located a pair of nozzles 15 and 16 connected at their lower ends to the float chamber 3 and open at their upper ends so as to deliver fuel therefrom when the upper ends are subjected to a suction. At the lower end of the vertical part of passage 4 just above the point where it merges with the horizontal passage is located a ring 18 which so directs the air flow as to cause the proper suction upon the nozzles 15 and 16 and proper mixing of the air and fuel passing through the passageway 4. The ring 18 is in axial alignment with the vertical part of the passageway 4 which passageway is somewhat wider at the point 19 at which the ring is fixed and tapers immediately above the ring at 20 from this wider portion 19 to a portion 21 of smaller diameter. The ring 18 comprises a body portion 22 through which there is a short constricted passageway 23 which widens at both ends and in which are located the ends of the nozzles 15 and 16. The passageway 23 extends in the same direction as the vertical part of the passage 4. The body 22 of the ring 18 is of smaller diameter than the sec-

105

130

tion 19 of the passage 4 in which it is located and radially directed fins 24 and 25 extend from the periphery of the body 22 to the wall of passage 4. Certain of the radially extending fins, those numbered 23, have small lugs 26 integrally formed therewith. These lugs fit into recesses 27 in the wall of the passage 19 to hold the ring 18 in position. The radial fins 24 and 25 extend helically about the axis of the ring so that the air which passes between them is given a whirling or spinning motion.

It will be noted that there are more of the radial fins on the side nearest the inlet and this serves to balance the flow of air through the openings between the radial fins. The more radial fins there are on a side the less is the area through which the air may pass and hence the less is the air supplied from that side.

The body 23 of the ring 18 extends somewhat below the radial fins 24 and 25 thus forming a pocket 28 for the retention of a supply of air under the radial fins.

In Fig. 4 the carburetor casting 1 is modified so that it provides a second inlet passage 31 for the air and the air entering through this passage is separated by the wall 32 from the air in passage 4. The wall 32 of the air passage 31 extends upwardly from the bottom of the carburetor and surrounds the lower part of the body 22 of the ring 18 thus supplying to the central opening in the ring 18 air taken into the carburetor through the passage 31 opening through the bottom thereof at 34. Further construction may be attached to the carburetor for controlling the air taken in through the opening 34 but this can be supplied by anyone skilled in the art and hence has not been shown. This construction may consist of piping, valves and any other mechanism for supplying the desired quantity of air in the proper condition to this part of the carburetor.

Fig. 7 shows a carburetor of the type illustrated in Fig. 4 with an air pump or supercharger 33 connected to one of the intakes of the carburetor so as to supply air under pressure to the openings between the radial fins. The supercharger or air pump is merely shown diagrammatically and may be of any of the conventional types, either the turbine or pump type being common.

When desired a supercharger may be used with the carburetor as illustrated in Figs. 1 and 2 or a supercharger might be connected to the opening 34 of the carburetor as shown in Fig. 4.

In the modification shown in the Figures 8, 9 and 10, the construction of the carburetor is slightly changed at the ring. The ring in this modification consists of a body portion 40 through which there is a short passage 41 which is narrow at a point near its upper end and tapers from this point towards either

end. Radial fins 42 extend from the body 40 to the wall of the passageway in which the ring is located and lugs 43 on some of the fins seat in niches in the wall to support the ring in place. The tops of the fins are tapered in this embodiment so that they come to a point as they near the body of the ring. The fins are not joined to the body of the ring all of the way to the top, but their inner edges are rounded outward at 44 and the outer side of the top part of the body 40 is rounded inward at 45. This minimizes the breaking of the flow of air caused by the fins.

The whole ring is set somewhat lower in this embodiment and the body portion especially does not extend so far upward. Above the ring a collar 47 is located. This collar has an enlarged portion 48 which rests upon the tops of the fins at their outer edges and is enclosed in the lower casting of the carburetor and a portion 49 of smaller diameter which extends upward into the upper carburetor casting. The passageway in the upper casting is straight and untapered in this embodiment. The collar 47 is rather short and has a large opening 50 therethrough which widens at both ends. Its effect is to direct the air from the openings between the fins towards the center of the passage and then permit a slight expansion of the gases to permit better mixing.

It will be noted that the lower part of the body 47 is somewhat longer in the embodiment of Fig. 8 and this sometimes is found advantageous as it tends to even the flow of air past the nozzles. It is contemplated that the collar 47 might be cast integrally with the ring or with the upper carburetor casting.

The above embodiments are given merely as illustrations of the preferred forms of the applicant's invention and other embodiments as included in the appended claims are within the scope of this invention.

I claim:

1. In a carburetor, the combination of means forming a main air passage and means forming a constriction therein comprising a ring of smaller diameter than said passage having a central passage therethrough and supported in said passage by radially extending fins there being a greater number of fins on one side of the ring than on the other and means in said central passage for supplying fuel to the air flowing therethrough.

2. In a carburetor, the combination of means forming a main air passage and means forming a constriction therein comprising a ring of smaller diameter than said passage having a central passage therethrough and supported in said passage by radially extending fins, the body of said ring extending beyond said fins in axial direction, there being a greater number of fins on one side of

the ring than on the other and means in said central passage for supplying fuel to air flowing therethrough.

3. In a carburetor, the combination of means forming a main air passage and means forming a constriction therein comprising a ring of smaller diameter than said passage having a central passage therethrough and supported in said passage by radially extending fins there being a greater number of fins on one side of the ring than on the other, means in said central passage for supplying fuel to the air flowing therethrough and means forming a separate passage for supplying air to said central passage.

4. In a carburetor, the combination of means forming a main air passage and means forming a constriction therein comprising a ring of smaller diameter than said passage having a central passage therethrough and supported in said passage by radially extending fins there being a greater number of fins on one side of the ring than on the other, means in said central passage for supplying fuel to the air flowing therethrough, and means for forcing air into said carburetor.

5. In a carburetor the combination of means forming a main air passage, means forming a constriction therein having a central passage therethrough and a series of passages therethrough surrounding said central passage, said surrounding passages being directly spirally around said central passage for giving the air passing through a spiral movement, means in said central passage for supplying fuel to the air flowing therethrough, means forming a separate passage for supplying air to said central passage and means for forcing air into said carburetor.

6. In a carburetor the combination of means forming a main air passage and means forming a constriction therein comprising a ring of smaller diameter than said passage having a central passage therethrough and supported in said passage by radially extending fins at least some of which are adapted to engage notches in the wall of the main passage, said fins extending spirally about the axis of said ring, means in said central passage for supplying fuel to the air flowing therethrough, means forming a separate passage for supplying air to said central passage and means for forcing air into said carburetor.

7. In a carburetor the combination of means forming a main air passage, means forming a constriction therein having a central passage therethrough and a series of passages therethrough surrounding said central passage, said surrounding passages being directed spirally around said central passage for giving the air passing therethrough a spiral movement, means in said central passage for supplying fuel to the air flowing therethrough, means forming a separate pas-

sage for supplying air to said central passage and means for forcing air into said main passage.

8. In a carburetor the combination of means forming a main air passage and means forming a constriction therein comprising a ring of smaller diameter than said passage having a central passage therethrough and supported in said passage by radially extending fins at least some of which are adapted to engage notches in the wall of the main passage, said fins extending spirally about the axis of said ring, means in said central passage for supplying fuel to the air flowing therethrough, means forming a separate passage for supplying air to said central passage and means for forcing air into said main passage.

9. In a carburetor the combination of a main air passage, means in said passage forming a constriction therein comprising a ring of smaller diameter than said passage, having a central passage therethrough and supported in said passage by radially extending fins the tops of which are narrower towards the ring than towards the wall of the main passage and means for supplying fuel to air flowing through said constriction.

10. In a carburetor, the combination of a main air passage, means in said passage forming a constriction therein comprising a ring of smaller diameter than said passage, having a central passage therethrough and supported in said passage by radially extending fins the tops of which are narrower towards the ring than towards the wall of the main passage, the outside of the top of the ring being rounded inwardly and the edges of the fins adjacent thereto being rounded outwardly to leave a groove between the said top and fins, a second constriction in said main passage formed by a collar in said passage located immediately above said ring and fins, and means for supplying fuel to air passing through said first constriction.

In testimony whereof I affix my signature.

WILLIAM M. THOMAS.
